JOHN BUCHANAN, INVENTOR

BY *Victor J. Evans*

ATTORNEY

UNITED STATES PATENT OFFICE.

JOHN BUCHANAN, OF NORTH BRADDOCK, PENNSYLVANIA.

CRYSTAL DETECTOR AND CLIP.

Application filed June 2, 1924. Serial No. 717,411.

This invention relates to holding and connecting devices, and more particularly to a crystal detector and clips for use in connection with radio receiving sets employing 5 detector crystals.

One of the main objects of the invention is to provide a device of the character stated of simple construction and operation which may be readily produced and applied at very 10 small cost. A further object is to provide a device in which the crystal is effectually held against displacement, the holding means being provided with sharp or pointed elements which contact with the crystal, these 15 elements, due to their small cross-area, replacing the usual small wire or "cat-whisker" commonly employed in connection with detector crystals. A further object is to provide simple and efficient means whereby the 20 crystal holder may be readily connected to the receiving set and the phones may be readily connected to the holder, it being understood that the holder is formed of electrical conducting material. A further object is to 25 provide a clip or securing device of simple and highly efficient construction which may be employed in place of the usual binding post for connecting together one or more electrical conductors. Further objects will 30 appear from the detail description.

In the drawings:—

Fig. 1 is a top plan view of the device as used;

Fig. 2 is a side view;

Fig. 3 is a fragmentary inner face view of one of the crystals securing and holding members;

Fig. 4 is a side view of the device adapted for use as a clip.

The device includes two strips of brass or other suitable material each of which is bent to provide a jaw or holding member 1 which is disposed at right angles to an arm 2 which is bent over upon itself to form an upper 45 arm 2^a disposed parallel with and closely adjacent to the upper surface of arm 2. The arms 2 and 2^a are connected by an eye 3 and arm 2^a is bent up to form a transversely extending recess or groove which forms, with 50 arm 2, a socket 4. The members thus formed are secured by screws *b*, or in any other suitable or preferred manner, to a panel base B with the jaws or holding members 1 disposed in spaced parallel relation to receive 55 between them a crystal C of galena or other suitable material. The eyes 3 and sockets

4 provide, in effect, sockets for reception of the terminal members 6 of flexible wires 7 which may be connected to the usual head phones, and for the terminal elements of 60 wires 8 by means of which the crystal is connected to the receiving set. This provides very simple and efficient means whereby the crystal is connected to the set and the phones may be connected to the crystal in 65 proper relation. Arm 2^a, due to its inherent resiliency, ensures that the terminal elements of the wires 7 and 8 will be securely held thus procuring proper contact, it being understood that the strips of brass used in 70 forming the holding and securing members are of proper gauge and resiliency to obtain this effect.

As will be noted more clearly from Fig. 3, each of the holding members or jaws 1 is cut 75 and punched to provide a plurality of inwardly projecting points 1^a. These points are disposed to contact with and grip crystal C thus effectually securing the crystal against displacement, the holding members 80 being held in close contact with the crystal due to their inherent resiliency, it being understood that these members are spread slightly when the crystal is inserted. The fine points 1^a contact with the crystal and, 85 due to their very small cross-area, act in the same manner as the "cat-whisker" which is frequently employed in crystal detectors, the points 1^a which contact with sensitive spots on the crystal remaining fixed relative to 90 the crystal so as not to be displaced by jars or movement of the receiving set. In this respect the device is decidedly superior to the ordinary type of crystal detector employing a "cat-whisker" as the "cat-whisker" is very 95 easily displaced from a sensitive spot on the crystal thus necessitating readjustment of the detector.

The arms 2 and 2^a provide a clip which may be used in connection with the crystal holding member 1 or, if desired, can be used to replace the usual binding post used in connection with receiving sets. In Fig. 4 I have shown the device used as a clip, the holding member 1 being omitted. In this device the strip of brass is bent to provide a horizontal arm or base 2^b extending from the lower end of arm 2, the clip being secured to a suitable panel or base B by a screw *c* or in any other suitable or preferred manner. As previously explained, the socket members 3 and 4 are adapted for reception 100 105 110

of the terminals of electric wires or conductors thus providing simple and efficient means whereby electrical connections may be readily established between two wires or conductors without the necessity of employing binding screws and similar elements. As will be understood the number of sockets provided in the clip may be varied as desired or necessary and other changes in details of construction and arrangement of parts of the invention may be resorted to without departing from the field and scope of the same, and I intend to include all such variations, as fall within the scope of the appended claim, in this application in which

a preferred form only of my invention is disclosed.

What I claim is:

A combined radio terminal and crystal holder comprising a pair of rightangular elastic metal strips apertured for set screws for mounting on an insulated support, the base element having a folded end forming an elastic terminal socket, the vertical member having indentations to elastically grasp a rectifying crystal.

In testimony whereof I affix my signature.

JOHN BUCHANAN.
